UNITED STATES PATENT OFFICE.

FRANK TUITTE, OF MENARDVILLE, TEXAS, ASSIGNOR OF ONE-HALF TO
HENRY VANDER STUCKEN, OF SAME PLACE.

SASH-FASTENER.

SPECIFICATION forming part of Letters Patent No. 593,706, dated November 16, 1897.

Application filed April 22, 1897. Serial No. 633,248. (No model.)

To all whom it may concern:

Be it known that I, FRANK TUITTE, a citizen of the United States, residing at Menardville, in the county of Menard and State of 5 Texas, have invented a new and useful Sash Holder and Lock, of which the following is a specification.

This invention relates to certain improvements in sash holders and locks, its object 10 being to provide a simple, cheap, and efficient device of this character which may be applied to either the upper or lower sashes of windows in general use at the present time without materially injuring them and without 15 requiring the aid of a skilled mechanic.

The invention will be fully described hereinafter, and then particularly pointed out in the claims.

In the drawings, Figure 1 is a perspective 20 view of a portion of a window and its frame, showing my invention applied thereto. Fig. 2 is a front view of a portion of the lower sash and the frame, on an enlarged scale, showing the manner of applying my invention thereto. Fig. 3 is a similar view of a portion 25 of the upper sash or frame, on an enlarged scale, showing the manner of applying my invention thereto. Fig. 4 is a detail perspective view of the spring-catch. Fig. 5 is a detail 30 perspective view of a portion of the rack-bar used for the lower sash.

Similar reference-numerals indicate similar parts in the several figures.

1 indicates the window-frame, 2 the inner 35 guide-strip, and 3 the parting-strip. The lower window-sash is indicated by 4 and the upper one by 5. The rack-bar is marked 6 and is provided with a series of teeth, each of which has a horizontal flat face 7 and a vertically-inclining face 8. The bar is provided 40 with a flange 9 at the front side of the teeth, which projects outwardly beyond the plane of the teeth and serves as a guide to prevent the spring-catches from moving laterally out 45 of engagement with the teeth. At the lower end of the rack-bar for the lower sash the tooth portion of the bar is cut away, as indicated at 10, thereby forming a square-shouldered recess, of which the flange 9 forms one 50 of the side walls and the side rail of the sash 4 the other side wall. The function of this

recess will be referred to hereinafter. The rack-bar for the lower sash is secured to the inner guide-strip 2 close up to the sash, and the rack-bar for the upper sash is secured to 55 the parting-strip 3, and this bar is similar to that used for the lower sash, except that the recess 10 is omitted. When the upper rack-bar is used, it will be necessary to cut a recess in the top rail of the lower sash to enable it 60 to pass over the rack-bar. These rack-bars will preferably be made of iron, and it is my intention to make them in sections varying in length from eight to twelve inches. By this means the rack-bars can be fitted to any- 65 sized window without having to cut the bars.

The spring-catch consists of a strip of spring metal 11, preferably steel, secured at one end to a lug 12, projecting outwardly from a plate 13. This plate is provided with openings 14 70 for the passage of screws or similar fastening devices, by means of which the plate is secured to the window-sash. The spring-strip is bent to form a hook 15, the outer arm 16 of which is straight and arranged in substantially a horizontal plane. The end of the arm 16 is provided with a return-bend, as indicated at 17, for a purpose to be hereinafter referred to. The arms of the hook 15 and the bent end of the outer arm 16 all lie in the 75 same vertical plane.

Two spring-catches are secured to the lower sash, one above the other, and these are oppositely disposed in such manner that the lower one has its hook 15 projecting upwardly and 80 adapted to enter the recess 10 in the rack-bar, and the upper one has its hook projecting downwardly and adapted to engage with its horizontal arm 16 the flat faces 7 of the teeth in the rack-bar. When the parts are in this 85 position, it is evident that the lower spring-catch serves as a lock and prevents the lower sash from being raised, and in order to raise the sash the hook of the lower catch must be disengaged from the recess 10. This can be 90 accomplished by pulling the hook laterally, and the return-bend 17 serves as a convenient finger-hold for this purpose. When said hook is drawn out of the recess, the sash can be 95 raised and both spring-catches will ride up 100 over the teeth and the upper catch only will so engage with the teeth in the rack-bar as to

hold the sash elevated. In order to lower the sash, the upper hook must be held out of engagement with the teeth, while the lower one will slide over them.

5 Only one spring-catch is used on the upper sash, and that is so arranged that it will engage one of the teeth of the rack-bar when the sash is closed, and thereby lock the sash in its closed position. In order to lower the 10 sash, the hook must be disengaged from the teeth of the rack-bar, and as a convenient means of doing this I secure a cord 18 in the return-bend 17 of the hook and run it through the eye of a screw-eye 19, secured in the top 15 rail of the sash. By pulling on the cord 18 the hook will be disengaged and the sash may then be lowered to the desired point, when on releasing the cord the spring-catch will engage the nearest tooth in the bar and hold the 20 sash in position. In closing the upper sash the spring-catch will ride up over the teeth of the rack-bar.

An important feature of the above-described invention resides in the fact that the 25 construction of the catch adapts two relatively-reversed catches to be arranged with their finger-holds contiguous to each other for simultaneous pressure, and hence allows either catch to be operated without materially 30 changing the position of the operating-hand, one of the catches being designed to hold a sash at the desired elevation, while the other is designed to lock the sash at the limit of its 35 downward movement. It will be understood that changes in the form, proportion, and minor details of con-

struction may be resorted to without departing from the spirit or sacrificing any of the advantages of this invention.

What I claim is—

1. A reversible sash-holder for use in connection with fixed stops, the same having a spring-shank, for arrangement parallel with the path of a sash, a transverse arm arranged perpendicular to the path of the sash and terminating at one end in a finger-hold, and an inclined integral connecting portion between the other end of said arm and the shank, and meeting said arm at an acute angle to form a nose for engagement with said fixed stops, substantially as specified.

2. The combination with a window-frame having an attached rack, and a sliding sash mounted for movement parallel with the rack, of relatively-reversed catches mounted upon the sash for engagement with the rack, each catch having a spring-shank, disposed approximately parallel with the rack, and a transverse arm connected at one end with the shank by an interposed inclined portion to form an acute angle to engage the rack-teeth, and terminating at the other end in a finger-hold, and said catches being disposed with their transverse arms contiguous to each other, substantially as specified.

In testimony that I claim the foregoing as my own I have hereto affixed my signature in the presence of two witnesses.

FRANK TUITTE.
